UNITED STATES PATENT OFFICE.

GEORGE T. WILLIAMS, OF DENVER, COLORADO.

MATRIX-BAR FOR TYPE-CASTING MACHINES.

1,160,351.

Specification of Letters Patent. Patented Nov. 16, 1915.

Original application filed April 28, 1913, Serial No. 763,968. Divided and this application filed August 22, 1913. Serial No. 786,164.

To all whom it may concern:

Be it known that I, GEORGE T. WILLIAMS, a citizen of the United States, residing in the city and county of Denver and State of Colorado, have invented certain new and useful Improvements in Matrix-Bars for Type-Casting Machines; and I do declare the following to be a full, clear, and exact description of the invention, such as will 5 enable others skilled in the art to which it appertains to make and use the same, reference being had to the accompanying drawings, and to the letters and figures of reference marked thereon, which form a part of 10 this specification.

My invention relates to improvements in matrix bars for type casting machines.

The subject matter of this invention is divided out of my former application, Serial 20 No. 763,968, filed April 28, 1913, and entitled Improvements in type setting and casting machines.

In my present construction, each matrix bar carries a number of matrix members, 25 these members carried by each bar containing in the aggregate the entire set of characters employed in printing, and corresponding with those indicated on the keyboard of the machine with which the bars 30 are used. The number of matrix bars necessary in a machine adapted to handle them, needs to be equal only to the number of letters or characters employed in the longest line which it may be desired to cast. This 35 greatly simplifies the construction as compared with one in which there is a distinct matrix for each character employed as in the well known Mergenthaler type of machine.

40 The invention also includes a matrix bar having a plurality of fonts of matrix characters.

Having briefly outlined my improved construction, I will proceed to describe the same 45 in detail, reference being made to the accompanying drawings, in which is illustrated an embodiment thereof.

In this drawing—Figure 1 is a side elevation in detail illustrating one of the matrix 50 bars. Fig. 2 is a front view of a series of such bars in assembled relation. Fig. 3 is a fragmentary view showing a number of matrix bars in assembled relation for casting a line of type; the mold being indicated

by dotted lines. Fig. 4 is a face view of a 55 matrix bar having a plurality of fonts of matrix characters. Fig. 5 is a view illustrating a matrix bar operatively equipped for utilizing a plurality of fonts of matrix characters of different faces or styles. This 60 view also shows means coöperating with such a bar to utilize such characters.

The same reference characters indicate the same parts in all the views.

Let the numeral 17 designate the matrix 65 bars, each of which is composed of a vertically disposed forwardly located rigid member 28 from whose extremity relatively short parts 29 extend rearwardly and to whose forward extremities are movably connected the upper and lower portions 30 of a vertically disposed part 31. The rigid member 28 is provided with a tooth 36 which is employed in arresting the downward movement of the bar when employed in a 70 type casting machine. This part 31 is composed of members 32 upon which the matrix characters are formed. Hence, the parts 32 may be termed matrix members and are separated by parts 33 which together with 75 the parts 30 preferably consist of thin, light metal material whereby the structure which forms a support for the matrix members 32 is sufficiently yielding to permit the matrix members when assembled in operative relation for casting the line of type, to move out of vertical alinement with the other portions of the matrix bar. It should be explained 80 that these matrix members 32 are of different horizontal thicknesses as best illustrated 85 in Figs. 2 and 3. Each matrix member has a series of notches formed on one edge thereof corresponding in number with the characters in the opposite edge. In these views, 90 the upper matrix members are shown of the proper thickness for two point type, the members next below being of the proper thickness for four point type, while the lowermost members are of the thickness for six point type. Hence, it will be understood 95 that when these different members 32 are arranged in assembled relation and properly clamped to conform to the length 100 of the line of type, it will be necessary for portions of the part 31 of the matrix bar 17 to move out of the plane of the other portions of the same bar. For this reason, the spring parts 33 separating the matrix mem-

bers will be made of sufficient length to accomplish the purpose. This is also true of the upper and lower portion 30 of each part 31. In order to permit the aforesaid 5 movement, the parts 30 are movably connected at their upper and lower extremities with the rearwardly extending parts 29 and the parts 30 are slotted as shown at 34 and connected with the parts 29 by means of pins 10 35. It is evident that this construction will permit a limited degree of lateral movement of intermediate portions of the part 31 of the matrix bar. These matrix bars are well adapted for use with a machine of the character set forth in my aforesaid application, but it must be understood that they may be employed at least so far as the broad invention is concerned, with various other constructions.

20 Each of the matrix bars 17 carries a space band 89 vertically movable on the lower spring part 30 thereof, and when the matrix members 32 whose characters are to be utilized in casting the line of type or assembled, preparatory to the casting operation, all of the space bands 89 of the various bars are in positions below the series of matrix members 32 assembled in front of the mold 88. The first act for completing the casting 25 arrangement of the matrix members 32 after they have assumed their positions in front of the mold, is to clamp these members 32 of the series from the opposite ends in order to bring the series of matrix members into a 30 space exactly equal with the length of line of type to be cast. The next step is to actuate the space bands 89 whereby they shall be caused to pass between the matrix members 32 assembled in operative relation whereby 35 the said members shall be properly spaced for dividing the words of the line of type to be cast. This upward movement of the various space bands which are wedge-shaped may be accomplished through the medium 40 of any suitable mechanism and consequently having nothing to do specifically with this application.

It will be understood that the matrix characters, which are to be utilized in casting the line of type through the medium of the mold, are so arranged that when the mold is in place, these matrix characters will all be aligned horizontally with the inner extremity of the opening of the mold which fits tightly 50 55 against the matrix members.

This invention includes a matrix bar having a plurality of complete fonts of matrix characters. It may be well to explain that in printing trade parlance a font is a complete set of characters required for printing, 60 including upper and lower case letters, figures, punctuation marks, etc., ordinarily consisting of ninety characters.

In Fig. 4 of the drawing, such a bar is 65 illustrated, showing certain characters of

three fonts. The bar is broken away, however, as it is deemed impracticable and unnecessary to illustrate the three complete fonts of characters, as this would ordinarily necessitate the showing of 270 characters, as 70 above indicated. The drawing does, however, illustrate a matrix bar which, when unbroken or complete, would contain three complete fonts of characters—that is, a complete font of roman, a complete font of 75 italic, and a complete font of bold face type, all on one matrix bar or member.

In the construction illustrated in Fig. 5 of the drawing, a portion of a type casting machine is illustrated of the character disclosed 80 in my simultaneously pending application, Serial No. 763,968, in which assembly pins 38 are arranged to be projected rearwardly at different distances by operating levers 40, an adjustable spindle 204 being mounted in 85 the frame and provided on one side with a projection 205. When this spindle is so adjusted that its cam or projection is in the position shown in dotted lines in this view, the rearward movement of the lever arms 40 is limited, whereby the rearward movement 90 of their fingers 47 is correspondingly limited. Hence, when the spindle 204 is in the position shown by dotted lines, the lever arms 40 cannot move the pins 38 rearwardly 95 as far as when the spindle 204 is in the full line position. The difference in the extension or projection of the pins 38 rearwardly from the assembly frame when acted on by the fingers 47 of the lever arms 40, when the 100 spindle is in the two different positions, is indicated in this figure. In this form of construction, the tooth 36 of the matrix bars is notched, as shown in 206, whereby two supporting faces designated 207 and 208, 105 respectively, are formed, the face 207 being slightly forward of the face 208, the face 207 being also slightly more elevated than the face 208.

The object of this form of construction is 110 to make it practicable to support the matrix bar in position to utilize either of two adjacent matrix characters where one is arranged directly above the other, as for instance, referring to Fig. 4, the roman character or the bold face character of a matrix bar having a plurality of matrix characters of different faces, or styles. If the pin 38 is projected by a lever arm 40 when the spindle is in the dotted line position in Fig. 5, the rear extremity of the pin will be in position to stop the downward movement of the matrix bar when the face 207 of the tooth engages the face 209 of the pin, whereas if the pin is projected by a lever arm 40, when the spindle 115 204 is in the full line position, the pin will extend rearwardly somewhat farther so that its supporting face 209 will engage the face 208 of the tooth and consequently stop the downward movement of the bar at a slightly 120 125 130

higher elevation than when the face 207 engages the pin. Hence, if it is desired to utilize the lower matrix character of two different faces or styles, the spindle 204 will 5 be moved to occupy the full line position, whereby the pin 38 will be projected rearwardly to its limit of movement, and consequently stop the matrix bar in the more elevated position, whereas, if it is desired to 10 utilize a matrix character next above of the two under consideration, the spindle will be turned to the dotted line position, so that the assembly pin shall be projected to engage the face 207 of the tooth 36 of the 15 corresponding matrix bar.

While provision is made by the disclosure in Fig. 5 for utilizing two characters only of different faces or styles, or for handling a matrix bar having two fonts of characters, 20 it is evident that by adding another face to the tooth 36 and placing the same one-matrix-space lower than the face 208, provision will be made for supporting the matrix bar in position to utilize the italic A, 25 for instance, referring to Fig. 4. In this way, it is evident that means may be provided for utilizing a matrix bar having any number of fonts of typographical characters without in any way departing from the 30 spirit of the invention.

I claim—

1. A matrix bar, including a number of matrix members connected by interposed flexible strips, and a rigid body member 35 with which the flexible member is connected at its upper and lower extremities.

2. A matrix bar, including a flexible part composed of a number of distinct matrix members suitably spaced and connected to 40 permit independent lateral movement, and a rigid body member with which the flexible member is connected at its upper and lower extremities.

3. A matrix bar, including a flexible part composed of a number of distinct matrix 45 members of different thicknesses connected to permit the independent lateral movement thereof, and a rigid body member with which the flexible part is connected at its 50 upper and lower ends.

4. A matrix bar, including a number of spaced matrix members in which are formed characters varying in point units, the said members being connected by interposed laterally flexible metallic strips, and a rigid body member with which the flexible part is connected at its opposite ends.

5. A matrix bar, including a number of spaced matrix members, in each of which are 60 formed a plurality of characters varying in point units, the said members being connected by interposed laterally-flexible metallic strips, each bar also having thin metallic strips both above and below the terminal 65 matrix members, and a rigid body part with

which the flexible part is connected at the top and bottom.

6. A matrix bar, including a rigid body part and a number of spaced matrix members in which are formed characters varying 70 in point units, the said members being connected by interposed laterally flexible metallic strips, each bar also having thin metallic strips both above and below the terminal matrix members, the last-named strips 75 being movably connected at their extremities with the body of the bar.

7. A matrix bar composed of a rigid body part, and a number of distinct matrix members spaced by thin metal strips and having 80 similar strips extending above and below the terminal matrix members and movably connected with the body of the bar.

8. A matrix bar, including a flexible part composed of a number of matrix members 85 suitably spaced and connected by thin metallic strips, and a rigid body part to which the flexible part is connected at the top and bottom.

9. A matrix bar, including a flexible part 90 composed of a number of matrix members suitably spaced and connected by laterally yielding strips, and a rigid body part to which the flexible part is movably connected at the top and bottom.

10. A matrix bar, including a flexible part composed of a number of matrix members carrying characters varying in point units, said members being suitably spaced and connected by laterally yielding strips, 100 and a rigid body part to which the flexible part of the bar is movably connected at the top and bottom.

11. A number of matrix members carrying characters varying in point units and 105 connected by thin strips of metal, and similar metal strips extending both above and below the terminal matrix members, and a rigid body part to which the top and bottom metal strips of the flexible part are 110 movably connected.

12. A matrix bar composed of a rigid body part and a number of matrix members carrying characters varying in point units, the said members being movably connected with the body of the bar by thin leaf springs, the said members being spaced and connected by similar leaf spring parts.

13. A matrix bar, including a rigid U-shaped member, matrix members carrying 120 characters varying in point units, the said members being connected with the body part of the bar by ribbon or thin flat springs movably attached to the body part, the several matrix members being spaced and connected with each other by similar leaf spring parts, substantially as described.

14. A matrix bar including a rigid member, matrix members carrying characters varying in point units, the said members 125

- being connected with the body part of the bar by ribbon or thin flat springs movably attached to the body part, the several matrix members being spaced and connected with each other by similar ribbon or thin flat spring parts, and a space band slidably mounted on the ribbon or thin flat spring part connected with the lowermost matrix member.
15. A matrix bar including a body member, matrix members carrying characters varying in point units, the said members being connected with the body of the bar by ribbon or thin flat springs movably attached to the body part, the several matrix members being vertically spaced and connected with each other by similar ribbon or thin flat spring parts, and a space band slidably mounted on the ribbon or thin spring connected with the lowermost matrix member, the said space band being wedge-shaped for the purpose set forth.
16. A matrix bar, including a rigid body member, matrix members carrying characters varying in point units, the said matrix members being connected with the body part of the bar by ribbon or thin flat springs movably attached to the body part, the several matrix members being spaced and connected with each other by similar ribbon or thin flat spring members, each matrix member having a series of notches in one edge thereof, corresponding in number with the matrix characters therein.
17. A matrix bar, including a body part, matrix members carrying characters varying in point units, the said members being connected with the body part of the bar by ribbon or thin flat springs movably attached, the several matrix members being spaced vertically and connected with each other by similar ribbon or thin flat spring parts, each matrix member having a series of notches formed on one edge thereof corresponding in number with the characters

thereof, the body part of the bar having a tooth for the purpose set forth.

18. A matrix bar provided with a plurality of complete fonts of matrix characters, each font having a different face or style, the said bar being operatively equipped to utilize such characters.

19. A matrix bar, including a number of spaced matrix members in each of which is formed a plurality of characters varying in point units, the said members being connected by interposed laterally flexible metallic strips, each bar also having thin metallic strips both above and below the terminal matrix members, and a rigid body part with which the last named strips are connected.

20. A flexible matrix bar composed of a multiplicity of matrix members, each bearing a multiplicity of matrix characters, the said members of each bar being so flexibly connected as to permit lateral motion in either side direction between the various members thereof, and a rigid body part with which the flexible part is movably connected at the top and bottom.

21. A matrix bar provided with a plurality of fonts of matrix characters, each font having a different face or style, the bar being equipped with a tooth having a plurality of faces to facilitate the use thereof.

22. A matrix bar provided with a plurality of fonts of matrix characters, each font having a different face or style, the bar having a plurality of supporting faces to facilitate the use thereof.

23. A matrix bar provided with a plurality of complete fonts of matrix characters, each font having a different face or style.

In testimony whereof I affix my signature in presence of two witnesses.

GEORGE T. WILLIAMS.
